US00D977598S

(12) **United States Design Patent** (10) **Patent No.:** **US D977,598 S**
Wu (45) **Date of Patent:** **** Feb. 7, 2023**

(54) **SPINNING BIKE**

(71) Applicant: **Shanghai Wenjia Industrial Co., Ltd,**
Shanghai (CN)

(72) Inventor: **Leilei Wu**, Shanghai (CN)

(73) Assignee: **Shanghai Wenjia Industrial Co., Ltd,**
Shanghai (CN)

(**) Term: **15 Years**

(21) Appl. No.: **29/736,115**

(22) Filed: **May 28, 2020**

(51) LOC (14) Cl. **21-02**

(52) U.S. Cl.

USPC **D21/663**

(58) **Field of Classification Search**

USPC D21/662, 663, 664, 694, 698; D12/111
CPC A63B 2225/50; A63B 22/0605; A63B
71/0622

(57) **CLAIM**

The ornamental design for a spinning bike, as shown and described.

DESCRIPTION

FIG. 1 is a perspective view of a spinning bike showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of portion 8 shown in FIG. 1;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 2. The dash-dash broken lines in the figures illustrate portions of the spinning bike that form no part of the claimed design. The dot-dash broken lines represent boundaries of the enlarged portions and form no part of the claimed design.

1 Claim, 10 Drawing Sheets
